Inventor:

Edwin W. Grove Jr.
Cook, McCardle, D. V. & Co.

UNITED STATES PATENT OFFICE.

EDWIN W. GROVE, JR., OF ST. LOUIS, MISSOURI.

ACCUMULATING DEVICE.

Application filed May 10, 1922. Serial No. 559,905.

To all whom it may concern:

Be it known that I, EDWIN W. GROVE, Jr., a citizen of the United States of America, a resident of the city of St. Louis, in the 5 State of Missouri, have invented certain new and useful Improvements in Accumulating Devices, of which the following is a full, clear, and exact description, reference being had to the accompanying drawings, forming 10 a part of this specification.

This invention relates generally to accumulating devices and particularly to a device to be used in connection with an automatic machine whereby the articles formed 15 by said machine may be gathered until a predetermined number of said articles have been accumulated, when they will be delivered in a body to a box or other container.

The principal object of the invention is 20 to provide a simple and inexpensive device of the kind mentioned above, which may be attached to forming machines now in general use whereby the necessity of manually handling and counting the articles formed 25 is eliminated.

A further object is to provide an accumulating device which will overcome many of the difficulties encountered in the use of the counting devices heretofore used.

30 With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims here- 35 unto appended.

Fig. I is a plan view of a tablet-forming machine with my accumulating device attached thereto.

Fig. II is a side elevation of a portion of 45 the machine and the accumulating device shown in Fig. I.

Fig. III is a plan view of the tablet-receiving receptacle of my accumulating device, a fragment of the gate-actuating means 50 being shown.

Fig. IV is a longitudinal section of the mechanism shown in Fig. III.

Fig. V is a section on line V—V of Fig. IV.

55 Fig. VI is an enlarged fragmentary view

showing the mechanism for actuating the gate.

To illustrate one application of my invention, I show in the drawings a machine of the type used to form medical or candy tablets, which comprises a base A provided with an enlarged upper portion B. The enlarged upper portion B is provided with an inclined spout C, the purpose of which will be hereinafter described. 60

65 Located immediately above the enlarged upper portion B is a lower rotatable member D and an upper rotatable member E. The rotatable members D and E are rotatably driven by means of a main shaft F which may be driven by any suitable power device (not shown).

The rotatable member D is provided with a plurality of holes G, each of which contains a die member in the form of a plunger H, and the rotatable member E is provided with an equal number of similar holes J, each of which contains a comparatively long spring-controlled plunger K. 70

75 Located in juxtaposition to the rotatable member D is a stationary ingredient-receiving trough L, which is adapted to receive the powdered ingredients from the receptacle M. The trough L is provided with an open bottom so that when the powdered ingredients are placed in said trough said powder will rest upon the upper face of the rotatable member D. 80

In the operation of the machine illustrated, the rotatable member D is rotated in the 90 direction indicated by the arrow in Fig. II of the drawing, and as the holes in said rotatable member pass under the trough L, said holes will be filled with powder, due to the fact that the plungers H in said holes 95 are drawn downwardly to provide powder-receiving spaces in said holes. When the holes which contain the powder pass around to the opposite side of the machine, the plungers K carried by the rotating member 100

E are engaged by a cam N, and said plungers are caused to move downwardly where they are engaged by the rotating roller P, whereby said plungers receive the final downward thrust. The plungers H carried 105 by the rotating member D are caused to move upwardly by mechanism which is not shown, at the same time that the plungers K are moving downwardly, consequently the powder in the holes G will be compressed 110

between the ends of the plungers H and K whereby the tablets are formed. After the forming of a tablet has taken place, the plunger K moves upwardly and the plunger H also moves upwardly until the lower face of the formed tablet is flush with the top face of the rotating member D, and when said tablet reaches a point adjacent to the spout C the inclined portion I' of the trough L will deflect said tablet into said spout. The foregoing matter briefly describes one type of tablet-forming machine which is now in general use, and as said mechanism forms no part of my invention, I do not deem it necessary to describe same any further.

The invention consists in a means for gathering the completed tablets and permitting same to accumulate until a predetermined number has been reached, when said accumulated tablets will be delivered in a body to a box or other container which has been previously properly located to receive said tablets.

1 designates an inclined receptacle which comprises a U-shaped body portion provided with a cover 2. The outer end of the receptacle 1 is provided with a discharge end 3 which extends downwardly at a greater angle than the body portion of said receptacle. By referring to Fig. I of the drawing it will be seen that the receptacle 1 is tapered, the body portion of said receptacle being of such width as to fit snugly between the upturned flanges of the spout C and the discharge end thereof being reduced in width so as to discharge the tablets into a comparatively small container. The receptacle 1 is secured in place in the spout C by means of a pair of set screws 4.

Formed at the upper edges of the side walls of the body portion of the receptacle 1 is a pair of ears 5, each of which is provided with an opening which receives a transverse oscillatory rod 6. The ears 5 are preferably provided with bushings 7 in which said rod 6 is journaled. Secured in any suitable manner to the transverse rod 6 is a gate 8 in the form of a flat piece of metal of the approximate width of the inside of the receptacle 1. The lower portion of said gate contacts with the lower inside face of the discharge portion of said receptacle, and said gate prevents any tablets which may find their way into the receptacle 1 from passing therethrough while said gate is in a closed position. One of the outer ends of the transverse rod 6 is bent to provide a crank arm 9 for a purpose to be hereinafter disclosed.

Fixed to an upright rod R which forms a stationary part of the machine is a collar 10, said collar being preferably formed in two parts which are secured together around said rod by means of screws or other fastening devices 11. Extending outwardly

from said collar 10 is a short rod 12 to which a trip arm 13 is pivotally secured, said trip arm being pivoted approximately at its center to said rod. Pivotally attached to the lower end of the trip arm 13 is a connecting member 14 which, with a similar connecting member 15 which is pivotally connected to the crank arm 9, serves to cooperatively connect the trip arm 13 to the oscillatory rod 6. The connecting members 14 and 15 are connected together by means of bolts 16 which pass through slots 17 in said members to permit the adjustment of said members relative to each other.

Secured to the rotatable head E is a split band 18, said band being provided with ears 19 which receive a bolt 20 whereby said band is clamped to said rotating head. Secured to the band 18 in any suitable manner is a block 21 which is provided with a projection 22.

Arranged around the oscillatory rod 6 at a point adjacent to the crank arm 9 is a torsional coil spring 23, one end of said torsional coil spring being fixed to the discharge end of the receptacle 1 and the other end thereof bearing against a portion of said crank arm.

The operation of my accumulating device is as follows:

Assuming that the parts of the machine and of the accumulating device are in the positions that they will assume immediately after the tablets which have previously accumulated in the receptacle 1 have been discharged therefrom, as each hole G in the rotating member D arrives at a point adjacent to the spout C a formed tablet will be discharged into said spout and consequently into the receptacle 1, wherein said tablets will be stopped by the gate 8. The member E, it will be remembered, rotates at the same time and at the same speed as the member D, consequently when the die-carrying members D and E have almost completed a revolution, during which time the desired number of tablets have been deposited in the receptacle 1, the projection 22 on the member E will be in position to again engage the upper end of the trip arm 13, and upon said projection engaging said trip arm the lower end thereof will be swung rearwardly, thereby causing the connecting members 14 and 15 to likewise move rearwardly, thus oscillating the rod 6 against the action of the spring 23, thereby swinging the gate 8 upwardly and permitting the accumulated tablets to pass from the receptacle 1. After the projection 22 has passed beyond the upper end of the trip arm 13 the spring 23 will return the parts to their normal positions.

I claim:

1. An accumulating device for a machine having a head for forming the articles

produced by said machine, comprising a receptacle adapted to receive a plurality of said articles, a hinged means within said receptacle, said hinged means being periodically actuated whereby said accumulated articles are permitted to pass from said receptacle, and means associated with said head adapted to periodically actuate said hinged means.

2. An accumulating device for a machine having a head for forming the articles produced by said machine, comprising a receptacle adapted to receive a plurality of said articles, a hinged means within said receptacle, said means being periodically actuated whereby said accumulated articles are permitted to pass from said receptacle, and means on said head adapted to periodically actuate said hinged means.

3. An accumulating device for a machine having a rotating head, comprising a receptacle adapted to receive a plurality of articles formed by said machine, a hinged means within said receptacle, said means being periodically actuated whereby said accumulated articles are permitted to pass from said receptacle, and means on said rotating head adapted to periodically actuate said hinged means.

4. An accumulating device for a machine having a rotating head, comprising a receptacle adapted to receive a plurality of articles formed by said machine, a hinged means within said receptacle, said means being periodically actuated whereby said accumulated articles are permitted to pass from said receptacle, and means for actuating said hinged means comprising a pivoted member, means connecting said pivoted member to the hinged means within the receptacle, and means on said rotating head of the machine adapted to periodically engage said pivoted member to actuate said hinged means.

5. An accumulating device for a machine having a rotating head, comprising a receptacle adapted to receive a plurality of articles formed by said machine, a hinged means within said receptacle, said means being periodically actuated whereby said accumulated articles are permitted to pass from said receptacle, and means for actuating said hinged means, comprising a pivoted

member, means pivotally secured to the lower end of said pivoted member whereby 55 said pivoted member is connected to said hinged means, and a projection on said rotating head of the machine adapted to periodically engage the upper end of said pivoted member to actuate said hinged 60 means.

6. An accumulating device for a machine having a rotating head, comprising a receptacle adapted to receive a plurality of articles formed by said machine, a hinged 65 means within said receptacle, said means being periodically actuated whereby said accumulated articles are permitted to pass from said receptacle, and means for actuating said hinged means, comprising a pivoted 70 member, means pivotally secured to the lower end of said pivoted member whereby said pivoted member is connected to said hinged means within the inclined receptacle, and a band encircling the rotating 75 head of the machine, said band being provided with a projection adapted to periodically engage the upper end of said pivoted member to actuate said hinged means.

7. An accumulating device for a machine 80 having a rotating head, comprising an inclined receptacle adapted to receive a plurality of articles formed by said machine, an oscillatory rod extending transversely of said inclined receptacle, one end portion 85 of said oscillatory rod being shaped to form a crank arm, a gate secured to said oscillatory rod and adapted to close one end of said inclined receptacle, and means whereby said rod is oscillated to swing said gate upwardly to permit the accumulated articles 90 to pass from the inclined receptacle comprising a pivoted member, connecting means one end of which is pivotally secured to the lower end of said pivoted member and 95 the other end thereof secured to the crank arm on the oscillatory rod, and a band encircling the rotating head of the machine, said band being provided with a projection adapted to periodically engage the upper 100 end of said pivoted member to actuate said hinged means.

In testimony that I claim the foregoing I hereunto affix my signature.

EDWIN W. GROVE, JR.
